(57) **CLAIM**

ornamental design for a welding hood, as shown and
described.

DESCRIPTION

FIG. 1 is a perspective view of a welding hood showing my
new design;

FIG. 2 is a front elevational view thereof, the rear elevational
view being a mirror image thereof;

FIG. 3 is a right-side elevational view thereof, the left-side
elevational view being a mirror image thereof;

FIG. 4 is a top plan view thereof;

FIG. 5 is a bottom plan view thereof; and,

FIG. 6 is an enlarged partial perspective view showing a
corner detail of the welding hood.

The broken lines in the drawings show environmental struc-
ture or are otherwise for illustrative purposes only and form
no part of the claimed design.
